UNITED STATES PATENT OFFICE.

CHARLES P. KIMBALL, OF PORTLAND, MAINE.

IMPROVEMENT IN BUGGY-BODIES.

Specification forming part of Letters Patent No. 125,817, dated April 16, 1872.

To all whom it may concern:

Be it known that I, CHARLES P. KIMBALL, of Portland, in the county of Cumberland and State of Maine, have invented a new and useful Improvement in Carriages; and I hereby declare the following to be a full, clear, and exact description of the same, reference being had to the accompanying drawing, which is hereby made a part of this specification, in which—

Figure 1 shows a view of a carriage-body in perspective, with the motion of the lifting side indicated by dotted lines. Fig. 2 shows a side elevation of a carriage-body, with the lifting part of the side thrown quite up or forward. Fig. 3 shows an inside view of one side of a carriage-body to show the structure thereof. Fig. 4 is an edge view of a carriage-side, showing the manner of fitting the edge of the lifting or moving part of the side into the fixed part of the same.

Same letters show like parts.

My invention relates to that kind of vehicle called box-buggies, or to any vehicle where the sides extend all around the body of the vehicle, so as to form a box or inclosed space for the occupants, the seat, &c. The comfort and beauty of the carriage is somewhat counteracted by a single inconvenience in their use. I refer to the necessity of being obliged to step over the somewhat high sides, both when entering and stepping out of the carriage. On the other hand, if the sides in front of the seat were left off, and nothing but the carriage-body constructed between the seat and the dasher, the character of the vehicle would be changed, and its usefulness and comfort for many purposes diminished. When, however, the sides are carried all around the body of the vehicle, which is always the case in what is termed the "box-buggy," the paint and var-

nish on the same soon become marred or scarred on the outside by reason of being frequently struck by the feet of persons getting in and out. My invention consists in hinging or pivoting a part of the sides in front of the seat, or the whole of such portion, so that the same can be turned up in a vertical plane when a person is entering or leaving the carriage, and then replaced when the need for its being lifted no longer exists. This will clearly appear from the drawing.

A is the body; B, the lifting or turning portion of the sides; C, the hinge or pivot. *b a* shows the method of joining the edges of the two parts of the sides at *c*. D shows a curved guide, fitting a slight notch or slot in the front end E to steady the motion of B, and aid in supporting it when in motion or turned up.

I am aware that attempts have been made to obviate the inconvenience of the sides of box-buggies, but, owing to the direction and manner in which the movable part was turned, have proved useless.

On the inside, as at *d*, a spring-catch may be attached, to hold the movable part B when shut down, as in Fig. 1, and so made and arranged that an upward pull of the hand, grasping a handle or finger-piece to raise the part B will at the same time unclasp the catch.

What I claim as my invention, and desire to secure by Letters Patent, is—

The combination of the piece B, the pivot C, the grooved ends *b a*, with the semicircular slide or arc, and the catch and handle, all for the purposes and in the manner herein set forth.

CHAS. P. KIMBALL.
